US0D1054249S

(12) **United States Design Patent** (10) **Patent No.:** **US D1,054,249 S**
(45) **Date of Patent:** **** Dec. 17, 2024**

(54) **BOTTLE LID**

(71) Applicant: **Ningbo Jufu Intelligent Technology Co., Ltd.**, Yuyao (CN)

(72) Inventor: **Guofu Yang**, Nanyang (CN)

(***) Term: **15 Years**

(21) Appl. No.: **29/862,684**

(22) Filed: **Dec. 12, 2022**

(51) **LOC (14) Cl.** **07-02**

(52) **U.S. Cl.**

USPC **D7/392.1**

CLAIM

The ornamental design for a bottle lid as shown and described.

DESCRIPTION

FIG. 1 is a perspective view of a bottle lid showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bottle lid, shown in an open configuration of use.

The broken lines in the drawings depict portions of the bottle lid that form no part of the claimed design.

1 Claim, 9 Drawing Sheets
